(57) **CLAIM**

The ornamental design for a wheel dolly, as shown and described.

DESCRIPTION

FIG. 1 is a top front perspective view of the wheel dolly.

FIG. 2 is a top front perspective view thereof.

FIG. 3 is a top rear perspective view thereof.

FIG. 4 is a top rear perspective view thereof.

FIG. 5 is a top front perspective view thereof, with the wheels rotated upwards.

FIG. 6 is a top front perspective view thereof, with the wheels rotated upwards.

FIG. 7 is a perspective view thereof shown within the environment of use.

FIG. 8 is a right-side view thereof.

FIG. 9 is a left-side view thereof.

FIG. 10 is a cross-sectional view thereof, taken along the line **10-10** shown in FIG. 14.FIG. 11 is a cross-sectional view thereof, taken along the line **11-11** shown in FIG. 14.

FIG. 12 is a front view thereof.

FIG. 13 is a rear view thereof.

FIG. 14 is a top view thereof; and,

FIG. 15 is a bottom view thereof.

The broken lines shown in FIG. 7 are included to show environment, and form no part of the claimed design.
